UNITED STATES PATENT OFFICE.

WILLIAM JAMES STEERE, OF ROCKWOOD, TENNESSEE.

ATTACHMENT FOR LOOPING-MACHINES.

1,292,527.

Specification of Letters Patent. Patented Jan. 28, 1919.

Application filed March 4, 1918. Serial No. 220,320.

To all whom it may concern:

Be it known that WILLIAM J. STEERE, citizen of the United States, residing at Rockwood, in the county of Roane and State of Tennessee, has invented certain new and useful Improvements in Attachments for Looping-Machines, of which the following is a specification, reference being had therein to the accompanying drawings.

10 This invention relates to an attachment for looping machines, and more particularly to a device for joining two edges of a knitted fabric, mainly for closing the gap or opening left in the toe portion of a seam-less stocking.

15 The object of this invention is the provision of means for cutting or eliminating automatically the chain thread made by a looping machine at the vacant intervals where no fabric is attached to the looper points for the needle to sew. It is to be understood that there is a large percentage of time lost by the operator having to break this chain by hand, and also very frequently there is 20 a long length of this chain left inside of the hose or stocking, which is very uncomfortable to the wearer, and to eliminate these disadvantages, I have produced my simple and efficient device as hereinafter specifically described and minutely illustrated in 25 the accompanying drawings.

With the foregoing object in view, other objects and advantages of my invention will appear in the following specification, and 30 be more particularly pointed out in the appended claims.

In the drawings:

Figure 1 is a top plan view of a device constructed in accordance with the present 35 invention, showing the same attached to a looping machine.

Fig. 2 is a view in front elevation of the device illustrated in Fig. 1.

Fig. 3 is a vertical, sectional view taken 40 on line 3—3, Fig. 1, looking in the direction of the arrows.

Fig. 4 is a vertical, sectional view taken on line 4—4, Fig. 1, looking in the direction of the arrows.

50 Fig. 5 is a perspective view of the guard plate.

Referring to the drawings by numerals, 1 designates the stationary part of the looper dial, and 2 is the base portion of the bracket 55 3. The base portion 2 of the bracket 3 is provided with a pair of apertured exten-

sions or lugs 4, through which extend securing screws 5 that attach the entire device to the part 1 of the looper dial.

A rotary brush 6 is attached to the lower 60 end of vertical shaft 6^a and secured to the top of brush 6 is a ratchet plate 7, which ratchet plate 7 is provided with the teeth 8, and secured to the under face of the ratchet plate 7, and evenly spaced around the same, 65 is a plurality of round-headed screws 9, Fig. 2.

Interposed between the hub portion 10 of the bracket 3 and the ratchet plate 7, is a swinging or rocker arm 11, which arm 11 carries, at its outer end, a spring-pressed pawl 12, and between the pawl 12 and the inner end of the rocker arm 11 is connected a link 13, which link 13 is pivotally connected to an extension 14 on part 15 of a looper; by 70 any movement, the rocker arm 11, carrying the spring-pressed pawl 12, may be actuated for imparting an intermittent rotary movement to the ratchet plate 7 and brush 6, the brush 6 carrying the depending bristles 80 as shown.

The hub portion 10 of the bracket 3 is provided with a primary, outwardly-extending lug 16 and an auxiliary outwardly-extending lug 17. The lugs 16 and 17 are each 85 provided with set-screws 18 for the purpose hereinafter described. Positioned in the primary lug 16 is an auxiliary bracket arm 19, and said arm 19 is held in position by means of the set-screw 18 carried by the lug 90 16. This auxiliary bracket arm 19 carries, at its lower end, the guard plate 20, the guard plate 20 being threaded, at 21, upon the lower end of the auxiliary bracket arm 19 and held securely on this bracket arm, 95 by a locking nut 22. The guard plate 20 is provided upon its front edge with guard flange 23, which guards the bristles of the rotary brush 6 as the brush is rotated.

Secured to the auxiliary lug 17 is a substantially U-shaped guard finger 24 (Fig. 2); the lower end 25 of the guard finger is positioned in the path of the bristles of brush 6 (Fig. 2) and causes the bristles to brush against the end 25.

100 I have assembled with my device, as an essential part thereof, a cutter made up of a stationary blade 26 and a movable swinging blade 27. The stationary blade 26 is secured in an inclined position, in a socket 28 110 on bracket 3, by means of a set-screw 29, upon which set-screw is positioned a washer

30, overhanging the upper edge of stationary blade 26, thereby securely retaining said stationary blade in an adjusted position upon the bracket, the inner end 31 of the 5 stationary blade being in alinement with the lower end of the bristles of brush 6 (Fig. 2).

A horizontal hub portion 32 is formed upon the bracket 3, and slidably mounted in this hub portion 32 is a shaft 33, which shaft 10 is provided with a spring 34 and locking collar 35. On the outer end of shaft 33 is a cutter-carrying bracket 36, which bracket is secured, in a set position, upon shaft 33 by a set-screw 37. This cutter-carrying bracket 15 36 is provided, on its inner face, with the movable blade 27, which blade 27 is retained in an adjusted position by the set-screw 29; the lower cutting edge 31^a of the blade 27 being positioned contiguous to the lower cutting edge 31 of the stationary blade 26.

A single round-headed screw 38 is carried near the inner end and upon the top of the cutter-carrying bracket 36, and this round-headed screw is adapted to be engaged by the heads of screws 9 carried by the ratchet plate 7, and as the screws 9 and screw 38 come in engagement, by reason of their round structure, they will ride over each other, but by reason of the cutter-carrying bracket 36 being able to swing downwardly, said bracket will be forced downward, as the heads of screws 9 pass over the head of screw 38, causing the cutter blade 27 to move downward, at its lower end, for cutting or severing a thread that is moved by the bristles of brush 6 in between the cutting edges 31 and 31^a of the blades of the cutter.

A coil-spring 39 is secured, at its lower 40 end, to the bracket 36 (Fig. 2), and at its upper end, it is secured to the outer end of a horizontal fixed pin 40 carried by bracket 3; this spring 39 exerts an upward pull upon the cutter-carrying bracket 36 for holding 45 the head or extension of screw 38 always in the path of movement of the heads of screws 9, so that, at certain intervals, by reason of the heads of screws 9 coming into engagement with the head of screw 38, the movable blade 27 of the cutter is operated for causing the cutting action for severing the strand.

A flat guard finger 41 is secured, at its inner end, by screw 42, to the side of the 55 bracket (Fig. 1), and this guard finger serves to keep the bristles of the brush 6 from coming into contact with the blades 26 and 27 of the cutter, notwithstanding they move close to the blades for directing the 60 strand or chain in between the cutting edges of the blades of the cutter.

Having described the several parts of my attachment, the specific operation is as follows:

65 It is to be understood that when connect-

ing my attachment for cutting the chain made by a looping machine at the vacant intervals between the hose or stocking, it is very desirable to have it set on the looper machine in such a position that the cutting 70 members or blades 26 and 27 will have the least chance of doing damage to the brasses in which the looper points are inserted, hence my reason for putting these cutting members or blades just back of these brasses instead of over the top of them. Now, as these brasses are of such a delicate nature, and their good condition so necessary to the perfect operation of the looper mechanism, it is obvious that to move the chain (which 80 lies down close to the brasses) in between the cutting members or blades 26 and 27, it would be necessary to use a member composed of material other than metal, hence I have used a bristle brush 6, as I deem such 85 a brush is the most advantageous. As the chain is liable to occur at any place along the circle of points near the brasses because the hose are sometimes of different widths, and also because the wish of the operator 90 is to put them on the points anywhere, regardless of the size, the brush 6 makes the cutting of the chain possible at any point where the chain occurs. The blades 26 and 27 are adjusted so that when they are open, 95 the opening is on a level with the top of the brasses or moving part of the dial, the cutting blades 26 and 27 are now ready to receive the chain, and said chain lies close to the brasses, therefore, the end of the bristles of the brush must be set down very close to the points and brasses to come in contact with the chain to sweep it in between the blades of the cutter. This operation 100 might not be possible but for the fact that 105 the chain possesses enough elasticity to allow brush 6 to carry it out of its true course and in between the blades of the cutter. I have described the movement necessary to cut the chain at the point or near 110 side where the chain is attached to the fabric of the hose. To sever the chain at the far side, the brush 6 still having hold of the chain, after it is cut the first time, by its rotary movement, continues to drag the 115 chain link on top of shelf or guard 20 (Fig. 5) keeping the chain taut until the dial in turning will bring the chain in between the two blades of the cutter. To insure the 120 chain staying on the guard 20, and also to insure of the chain being finally brought to the proper angle to place it between the blades, I have provided an extension or guard portion 23 on guard 20, which also guards against the brush losing control of the chain.

After the chain is severed on both sides, the brush continues to carry it along on the guard plate 20 until it is in the clear of the looper points, and I have provided a 130

wire bracket 24, bent down and under the ends of the bristles, at 25, this wire performing the function, at 25, of points or prongs or a sharpened edge, acting upon the bristles, so as to clean the bristles or rid the same of the chain if it happens to stick to the bristles.

When sweeping the chain in between the blades 26 and 27 of the cutter, the bristles of 10 brush 6 move very close to the cutting edges of the blades, and if not protected, might be injured by getting in between the blades, therefore, to prevent this happening, I provide the guard 41, which guard 41 is placed 15 so that its outer end is brought over the brasses in between the blades and the bristles of brush 6; this guard 41 holds the bristles off far enough to prevent them from coming in contact with the cutter blades. The 20 guard 41 also serves the purpose of keeping the chain from rising above the opening between the blades of the cutter when they are open (Fig. 2).

To drive my attachment, any kind of a 25 device will do, inasmuch as it is immaterial whether the dial moves continuously by gears or a belt or by ratchet movement; however, I have shown, as the preferred 30 form, the ratchet idea as explained. The looper dial moves very slowly, one point to a revolution of its drive shaft, so that it is not necessary to move the brush faster than will take care of the chain and its elasticity. I 35 find the ratchet movement is fast enough; to secure this movement, pitman or link 13 is connected to arm 14, which is clamped to the dial ratchet pawl 15, which pawl 15 secures its motion or movement from the main shaft by an eccentric cam, not shown.

40 I do not find it necessary for the blades of the cutter to go through the motion of cutting at every movement of the dial in all cases, as in the case of a machine that would be made for very thin work, the points might 45 be twenty four to the inch, and in that case, there would be such a small amount of chain passing by that it would only wear the blades out sooner, without accomplishing better results. Hence, I have used round-headed 50 screws 9, which can be inserted in the ratchet plates 7 at desired intervals to operate one to one, or one to four, as the number of points to the inch require. Some machines are six points to the inch, and in that case, 55 I would have to move blades one. The heads of screws 9 come in contact with the pointed head of screw 38, and the object of this function is to cause the cutting edge of the blades 26 and 27 to close together when 60 the heads of screws 9 pass over the head of screw 38. On the next movement of the ratchet wheel, the head of a screw 9 passes beyond screw 38 and the cutter bracket is free to rise and allow the blades to be 65 opened, as shown, for the next operation of

cutting a chain. This return to the normal position is accomplished by the spring 39 bringing the blade-carrying bracket 36 to its normal position, as clearly shown in Fig. 2.

The cutting blades 26 and 27 are held in 70 position through the medium of dove-tailed grooves and are clamped tightly by screws 29 and 29^a, both screws having dove-tailed slotted washers underneath the same, which washers fit the outer beveled edges of the 75 blades 26 and 27.

What I claim is:

1. In a mechanism of the class described, the combination with a support, of a bracket secured to said support, a shaft carried by 80 said bracket, a brush secured to said shaft, a ratchet plate secured to said shaft, a stationary and a movable blade supported upon said bracket, means coöperating with said brush for positively directing a chain of 85 loose stitches between knitted articles between the blades, said ratchet plate and movable blade provided with means for intermittently swinging the movable blade for severing the chain placed between the 90 blades, and means for rotating said ratchet plate for causing the intermittent swinging of the movable blade.

2. In a mechanism of the class described, the combination with a support, of a bracket 95 carried by said support, said bracket provided with a rotary brush and with a cutter actuating means movable with said brush, a cutter carried by said bracket and provided with a movable blade actuated by 100 said cutter-actuating means carried by said brush, and guard means for said brush and constituting guiding means for directing a chain of loose stitches between knitted articles between the blades of said cutter. 105

3. In a mechanism of the class described, the combination with a support, of a bracket detachably secured to said support, said bracket provided with a shaft, a rotary brush secured to the inner end of said shaft, a ratchet plate secured to said shaft adjacent said brush, headed members secured to the under face of said ratchet plate, a rocker arm provided with a pawl and positioned upon said shaft between the bracket and said ratchet plate, said pawl engaging said ratchet plate for intermittently rotating the same, an auxiliary bracket attached to said first-mentioned bracket, a guard plate provided with a vertical flange detachably secured to the lower end of said auxiliary bracket, said guard plate resting against the bristles of said brush, a stationary blade adjustably secured to said first-mentioned bracket, a swinging blade-carrying bracket 110 positioned upon said first-mentioned bracket, an adjustable blade secured to said swinging blade-carrying bracket, a flat guard finger interposed between the bristles of the brush and said blades, secured at its inner end, to 115 120 125 130

- the side of the first-mentioned bracket, and a substantially U-shaped guard finger carried by said bracket and having its lower inner end engaging the bristles of the brush.
- 5 4. In a mechanism of the class described, the combination with a support, of a stationary and a swinging blade carried by said support, a brush, a projection, means supporting said projection on said brush,
- 10 means coöperating with the swinging blade and the projection for swinging the swinging blade at predetermined intervals, and means coöperating with the brush for positively directing a chain or thread between
- 15 said blades.
5. In a mechanism of the class described, the combination with a support, of a bracket carried by said support, a stationary blade fitted in a portion of the bracket, means re-
- 20 taining the stationary blade in an adjusted position upon said bracket, a spring-pressed shaft carried by said bracket, a blade-carrying bracket detachably secured to said spring-pressed shaft, a blade adjustably se-
- 25 cured in a portion of said blade-carrying bracket, said blades being normally held against each other, a detachable extension carried by said blade-carrying bracket near its inner end, and a brush for directing a
- 30 strand or a chain in between the blades, means movable with said brush and engag-
- ing said detachable extension of the blade-carrying device for intermittently swinging said blade-carrying bracket and its blade upon the first-mentioned bracket for severing a strand or a chain between the blades. 35
6. In a mechanism of the class described, the combination with a support, of a cutter carried by said support, a brush coöperating with said cutter for positively directing a strand or chain between the blades of the cutter, a guard plate positioned against the brush, and a guard finger having its inner end positioned against the brush to one side of the guard plate. 40
7. In a mechanism of the class described, the combination with a support, of a bracket carried by said support, a cutter device provided with blades carried at one side of said bracket, a brush device carried upon the outer end of said bracket and being adapted to direct a strand or a chain between the blades of the cutter device, guard means interposed between the blades and the brush device for preventing any portion of the brush device entering between the blades, and a guard plate positioned under said brush. 45

In testimony whereof I hereunto affix my signature.

WILLIAM JAMES STEERE.
